UNITED STATES PATENT OFFICE.

JOHN C. DUEBER, OF NEWPORT, KENTUCKY.

DESIGN FOR A WATCH-CASE.

SPECIFICATION forming part of Design No. 14,997, dated May 13, 1884.

Application filed February 25, 1884. Term of patent 7 years.

To all whom it may concern:

Be it known that I, JOHN C. DUEBER, a citizen of the United States, residing at Newport, in the county of Campbell and State of Kentucky, have invented a certain new and original Design for Watch-Cases, of which the following is a specification, reference being had therein to the accompanying drawings.

My design consists in a series of small balls around the rim, center, or band of a watch-case, said balls being combined with larger projecting ornaments of any appropriate character. Several illustrations exhibiting this feature of my design are shown in the annexed drawings, in which—

Figure 1 is a side elevation of a watch-case embodying one form of my design. Figs. 2, 4, 5, and 6 are enlarged side elevations of portions of watch-cases, showing the same design having different combinations of projecting ornaments. Fig. 3 is an enlarged vertical section of the arrangement seen in Fig. 2.

A represents the rim, center, or band of a watch-case, which center, as seen in Fig. 1, is

armed with a series of swells or convexities, 25 B, between which convexities are located the balls C, the latter being of such a diameter and so located as not to project beyond the outer margin of said swells; but, as seen in Figs. 2 and 3, the balls are located on opposite sides 30 of the swells and about in line with the centers of the latter. Fig. 4 shows the balls located at the bottom of coves D. Fig. 5 shows another form of cove, and Fig. 6 represents the balls seated in angular notches E. 35

I claim as my invention—

The design for a watch-case herein shown and described, the same consisting of a series of balls, C, displayed around the periphery of the case and combined with projections of relatively greater size than said balls. 40

In testimony whereof I affix my signature in presence of two witnesses.

JOHN C. DUEBER.

Witnesses:

JAMES H. LAYMAN,
S. S. CARPENTER.
